UNITED STATES PATENT OFFICE.

GEORGE THOMAS BUCKHAM, OF WESTMINSTER, LONDON, AND FRANK SMITH, OF WOLVERHAMPTON, ENGLAND, ASSIGNEES TO VICKERS LIMITED, OF WESTMINSTER, ENGLAND.

CARRIAGE FOR BREECH-LOADING GUNS.

1,289,642.

Specification of Letters Patent.

Patented Dec. 31, 1918.

Application filed October 9, 1915. Serial No. 55,123.

To all whom it may concern:

Be it known that we, GEORGE THOMAS BUCKHAM and FRANK SMITH, both subjects of the King of Great Britain, residing, respectively, at Vickers House, Broadway, Westminster, in the county of London, England, and Pelham street, Wolverhampton, in the county of Stafford, England, have invented certain new and useful Improvements in or Relating to Carriages for Breech-Loading Guns, of which the following is a specification.

This invention relates to cycle side cars adapted to serve as carriages for automatic and quick-firing guns.

According to the invention the gun is carried by an arm or bracket connected to the side car framework in such a manner that the said arm or bracket can be swung into a position for enabling the gun to be fired in a forward direction or into a position for enabling the gun to be fired in a rearward direction as desired. The seat for the gunner may also be connected to the said arm or bracket so that it moves during the adjustment of the gun to either of its aforesaid positions. The arm or bracket is preferably inclined to the vertical and it may then become necessary to raise it, during the swinging movement, in order to clear the framework of the side car and the cycle to which the side car is attached. For this purpose the arm or bracket may be pivotally mounted on a turntable or other support movable about a vertical or approximately vertical axis and preferably carried by the side car framework at a position approximately midway between its ends. The gunner's seat may also require to be raised and it would then be connected to the turntable in a similar manner. The arm or bracket and the pillar or arm carrying the seat may be connected together in such a manner that the raising of the arm or bracket lifts the seat. When the gun has been adjusted to fire in either the forward or the rearward direction as aforesaid, it is supported in the firing position by a suitable portion of the side car framework without being disconnected from the aforesaid arm or bracket. When the gun has a tripod mounting as is usually the case with automatic guns, the gun together with the tripod mounting in its folded condition may be detachably con-

nected to the arm or bracket. Should occasion arise the gun and its mounting can be removed from the side car and used on the ground in the ordinary manner.

An ammunition box and foot-rests for the gunner may be so fixed to the aforesaid arm or bracket as to follow the gun in its swinging movement.

In order that the said invention may be clearly understood and readily carried into effect the same will now be described more fully with reference to the accompanying drawings, in which:—

Figure 1 is an elevation partly in section showing the gun and the gunner's seat in position on the side car for forward firing; the gun illustrated is of the Maxim type with a tripod mounting, the gun and mounting being shown in broken lines.

Fig. 2 is a corresponding plan but with the gun and its tripod mounting together with the gunner's seat removed to show certain parts more clearly.

Fig. 3 is a view corresponding to Fig. 1 but with the gun and gunner's seat in position for rearward firing, part only of the gun being shown in broken lines.

A is the gun which, together with its tripod, is mounted on the bed plate B forming part of the inclined arm or bracket C. The said arm or bracket is provided with an enlarged portion or foot C¹ which has a sleeve C² surrounding a horizontal transverse stationary pivot pin D carried by the turntable E. The turntable has a vertical pivot F mounted in a bearing G carried by and located in front of the junction piece H which connects together the cross members a b c of the side car chassis or framework. In the embodiment shown the chassis comprises lower side tubular members d d and upper curved side tubular members e e, together with upper transverse tubular members f f and lower transverse tubular members g g. The upper transverse members f f at the front and rear of the chassis carry bosses or collars h h between which the seating B' of the bed plate B is adapted to rest in either of its two positions so as to prevent lateral movement thereof. The underface B² of the seating B' is curved to enable it to rest firmly on the transverse member f. The upper side members e are rigidly secured to the lower side members d of the chassis by

strengthening tubes i i i . The lower side members d d and the rear transverse members g g serve to support the outer ends of the cross members a , b , c which are connected together at their inner ends by the aforesaid junction piece H . The gunner's seat L (which may be of any appropriate construction) has a part K by which it is connected to an arm J which is pivotally mounted at its inner end on a transverse pin I carried by sockets e^x e^x forming part of the turntable E . The said arm J also carries at its outer extremity a block M which has a curved underface M' so that the block rests 10 securely on the tubular member c of the chassis when the parts are in the position shown by Fig. 1 for forward firing. A transverse groove M^2 is also formed in the block M adapted to engage the lower transverse tubular member g when the parts are 15 in the position shown by Fig. 3 for rearward firing. The said enlarged portion or foot C^x of the arm or bracket C carries a short arm or extension O having a forked 20 extremity P which engages a pin N' carried by a pair of lugs N , N forming part of the inner end of the said arm J . Owing to this arrangement it will be apparent that when the arm or bracket C is turned upward about the transverse pin D , the arm J will also be turned upward about the pin I clear of the chassis, so that turntable E can 25 be turned about the bearing G in order to swing the gun and seat from the forward to the rearward position or vice versa.

Pivottally connected at P' to the bed plate seating B' are a pair of foot-rests P for the gunner. The said foot-rests are adapted to be raised about the pivotal connection P' before the gun and gunner's seat are operated and for this purpose the said foot-rests are connected by means of hinged links p' , p^2 , p^3 to collars p^4 p^5 carried by the arm or bracket C . The link p^2 is slidably 40 mounted in a bearing provided in the said collar p^5 and is adapted to be held normally in a fixed position by means of a wing nut p^6 . By loosening the nut p^6 the foot-rests can be raised, the link p^2 sliding in the bearing in the collar p^5 and being secured by 45 means of the nut p^6 so as to hold the foot-rests in the raised position.

The spade K' of the trail member k of the gun tripod is adapted to be supported by a pair of resilient blocks or buffers k^2 k^2 50 fitted to the foot C^x carried by the turntable E . The other two legs k^3 , k^3 of the tripod may be connected to the trail member K by straps or the like.

60 An ammunition tray Q and an upper shield R are attached to the bed plate B and are adapted to be swung about the bearing G simultaneously with the gun and tripod, the seat and the foot-rests. A lower shield S is also provided to protect the gun-

ner when firing in a forward direction. The foot-rests P are provided with a flange q which is curved at its upper end q' so as to fit closely around and beneath one or other of the transverse members f f when 70 the foot-rests occupy their normal position and thus lock the bed plate firmly in place at the front or the rear of the chassis.

The side car is attached to the cycle in the usual manner by means of attachment 75 members, part of one of these members being shown at T in Fig. 2.

In swinging the gun from the front position shown by Fig. 1 to the rear position shown by Fig. 3 the foot-rests P are first 80 raised and secured in their raised position. The act of raising the foot-rests disengages the curved end q' of the flange q from the transverse member f so that the bed plate can be raised in a vertical plane by turning 85 the arm or bracket C around the horizontal axis or pivot pin D . The act of turning the arm or bracket around the pivot pin D actuates the bifurcated arm O , which by depressing the pin N' on the arm J , causes 90 the latter to turn upwardly about the axis pin I and elevate the gunner's seat. When the gun and gunner's seat have been raised to an extent sufficient to clear the side car and the cycle, the gun and its tripod together 95 with the gunner's seat, the foot-rests, the ammunition box and the upper shield can be swung around the vertical axis or pivot G in a horizontal plane by means of the turntable E , so as to bring the gun into the 100 rear position shown by Fig. 3. The arm or bracket is then depressed to lower the bed plate onto the upper end member f between the bosses or collars h , h , the arm J and the gunner's seat being simultaneously depressed to bring the block M on the arm J into engagement with the transverse member g of the cycle car framework. The nut p^6 105 is then released and the foot-rests lowered. The curved end q' of the flange q thereupon 110 engages beneath the upper end member f and locks the bed plate B' firmly in position, whereupon the gun is ready for rearward firing.

We wish it to be understood that although 115 we have described the embodiment of our invention in connection with a Maxim gun having a tripod mounting, the gun may be of any other type and if desired may be permanently attached to the aforesaid swinging 120 arm or bracket C .

What we claim and desire to secure by Letters Patent of the United States is:—

1. A cycle side car comprising an arm or bracket, an automatic or quick firing gun 125 carried by said arm or bracket, means for connecting said arm or bracket to the cycle framework in such manner that the gun can be swung into a position where it can be fired in a forward direction or into a posi- 130

tion where it can be fired in a rearward direction, and means for supporting said arm or bracket in one or other of two positions, said means being disposed at the front and 5 at the rear of the side car.

2. A cycle side car comprising an arm or bracket, an automatic or quick firing gun carried by said arm or bracket, means for connecting said arm or bracket to the cycle framework in such manner that the gun can be swung into a position where it can be fired in a forward direction or into a position where it can be fired in a rearward direction, means for supporting said arm or bracket 10 in one or other of two positions, said means being disposed at the front and at the rear of the side car, a gunner's seat, and means for connecting said seat to said arm or bracket in such manner that during the adjustment of the gun for forward or rearward firing the gunner's seat will move simultaneously therewith.

3. A cycle side car comprising an arm or bracket, an automatic or quick firing gun carried by said arm or bracket, means for connecting said arm or bracket to the cycle framework in such manner that the gun can be swung into a position where it can be fired in a forward direction or into a position 25 where it can be fired in a rearward direction, a gunner's seat, means for connecting said seat to said arm in such manner that during the adjustment of the gun for forward or rearward firing the gunner's seat 30 will move simultaneously therewith, and footrests for the gunner connected to said arm or bracket so as to participate in its movements.

4. A cycle side car comprising an arm or bracket, an automatic or quick firing gun carried by said arm or bracket, means for connecting said arm or bracket to the cycle framework in such manner that the gun can be 40 swung into a position where it can be fired in a forward direction or into a position where it can be fired in a rearward direction, a gunner's seat, means for connecting said seat to said arm in such manner that during the adjustment of the gun for 45 forward or rearward firing the gunner's seat will move simultaneously therewith, footrests for the gunner hinged to said arm or bracket and means for adjusting said footrests relatively to this arm or bracket.

5. A cycle side car comprising an arm or bracket, an automatic or quick firing gun carried by said arm or bracket, means for connecting said arm or bracket to the cycle framework in such manner that the gun can be 55 swung into a position where it can be fired in a forward direction or into a position where it can be fired in a rearward direction, a gunner's seat, means for connecting said seat to said arm or bracket in such manner that during the adjustment of the gun 60

for forward or rearward firing the gunner's seat will move simultaneously therewith, foot-rests for the gunner, and a shield for the gunner, said foot-rests and said shield being connected to said arm or bracket 70 so as to participate in its movements.

6. A cycle side car comprising an arm or bracket, an automatic or quick firing gun together with its tripod mounting carried by said arm or bracket, and means for connecting said arm or bracket to the cycle framework in such manner that the said gun and its tripod mounting can be swung on said arm or bracket into a position where it can be 75 fired in a forward direction or into a position where it can be fired in a rearward direction.

7. A cycle side car comprising an arm or bracket, an automatic or quick firing gun together with its tripod mounting carried 80 by said arm or bracket, means for connecting said arm or bracket to the cycle framework in such manner that the said gun and its tripod mounting can be swung on said arm or bracket into a position where it can be 85 fired in a forward direction or into a position where it can be fired in a rearward direction, a gunner's seat, and means for connecting said seat to said arm or bracket in such manner that during the adjustment of 90 the gun for forward or rearward firing the gunner's seat will move simultaneously 95 therewith.

8. A cycle side car comprising an arm or bracket, an automatic or quick firing gun 100 together with its tripod mounting carried by said arm or bracket, means for connecting said arm or bracket to the cycle framework in such manner that the said gun and its tripod mounting can be swung into a position where it can be fired in a forward direction or into a position where it can be fired in a rearward direction, a gunner's seat, means for connecting said seat to said 105 arm or bracket in such manner that during the adjustment of the gun for forward or rearward firing the gunner's seat will move simultaneously therewith, foot-rests for the gunner, and a shield for the gunner, said foot-rests and said shield being connected 110 to said arm or bracket so as to participate in its movement.

9. A cycle side car having an arm or bracket carried by the side car chassis and capable of swinging from front to rear of 120 the side car, an automatic or quick firing gun carried by said arm or bracket, footrests for the gunner connected to the said arm or bracket, and means carried by said foot-rests for rigidly securing the said arm 125 or bracket to the side car chassis.

10. A cycle side car having an arm or bracket carried by the side car chassis and capable of swinging from front to rear of the side car, an automatic or quick firing 130

gun carried by said arm or bracket, foot rests for the gunner connected to the said arm or bracket, means carried by said foot rests for rigidly securing the said arm or bracket to the side car chassis, a gunner's seat, and means for connecting said seat to said arm or bracket so that said seat will move simultaneously therewith.

11. A cycle side car having a support carried by the side car framework, said support being capable of swinging about a vertical axis, a horizontal axis pin carried by said support, an inclined arm or bracket adapted to swing about said horizontal axis pin, an automatic or quick firing gun carried by said inclined arm or bracket, and means forming part of the side car framework for rigidly supporting said inclined arm or bracket either at the front or at the rear of the side car.

12. A cycle side car having a support carried by the side car frame work said support

being capable of swinging about a vertical axis, a horizontal axis pin carried by said support, an inclined arm or bracket adapted 25 to swing about said horizontal axis pin, an automatic or quick firing gun carried by said inclined arm or bracket, a gunner's seat, an arm carrying said seat, means for causing said arm to swing about a horizontal axis 30 simultaneously with the movement of the said inclined arm or bracket about its horizontal axis pin, and means forming part of the side car framework for rigidly supporting said inclined arm or bracket either 35 at the front or at the rear of the side car.

In testimony whereof we affix our signatures in the presence of two witnesses.

GEORGE THOMAS BUCKHAM.
FRANK SMITH.
